BRISTLE CLAMPING DEVICE

Charles F. Werkheiser, Burlington, Vt., assignor
to E. B. & A. C. Whiting Company, Burlington,
Vt., a corporation of Vermont

Application June 17, 1947, Serial No. 755,050

6 Claims. (Cl. 300—18)

1

This invention relates to an improved mechanism for clamping bristle, animal hair, various types of fibrous materials, and mixtures thereof, while conveying same through a treatment step and, while not limited thereto, is particularly adaptable for incorporation in a machine for combing these materials transported by a conveyor past a continuously moving comb.

In the manufacture of brushes, and brooms, preparation of the filling materials such as bristle, animal hair, various types of fibrous materials, and mixtures thereof, machines have been heretofore utilized for automatically subjecting a generally heterogeneously disposed mass of fibrous materials or bristles to a combing action so as to effect the side by side alignment of such fibers or bristles. For reference convenience, such materials will be hereafter generically referred to as bristles. In the machines heretofore known, the bristles are disposed upon a conveyor constituting a pair of spaced flexible chains, which are so located with respect to the average length of the bristles that the bristles project laterally a substantial distance beyond both chains. The bristles are then moved successively past two combs, which are continuously moving and so disposed as to intersect the path of the bristles at about the center of the bristles and to pass through the bristles in opposite directions outwardly toward their ends. When the bristles reach the point where they are to be operated on by the comb, it is obviously necessary that the end of the bristles which is not being worked on by the comb be tightly clamped with respect to the conveyor to prevent the entire mass of bristles from being combed off the conveyor. Such clamping action also has the effect of permitting the comb to eliminate any extremely short bristles, inasmuch as the ends of the short bristles would not be engaged by the clamping devices and hence such short bristles would be pulled out of the mass of longer bristles and discarded by the comb.

In the clamping mechanisms heretofore utilized, the clamping effect on the bristles was not sufficiently positive to insure that all bristles of proper length would be retained on the conveyor. Furthermore, certain bristle or fibrous materials, particularly very fine materials, could not be satisfactorily combed by machines employing the known clamping devices.

Accordingly, it is an object of this invention to provide an improved clamping device for securing one end of each of a mass of bristles or similar fibrous materials on a moving conveyor.

while the other end thereof is worked on by a tool, such as a comb.

A particular object of this invention is to provide an improved clamping mechanism for a bristle combing machine characterized by the provision of cooperating surfaces of rubber or flexible resilient composition for effecting a clamping action upon the bristles as they are moved through the working zone of the comb.

The specific nature of this invention as well as other objects and advantages thereof will become apparent to those skilled in the art from the following detailed description of the annexed sheet of drawings which, by way of preferred example only, illustrate one specific embodiment of the invention.

On the drawings:

Figure 1 is an end elevational view of a bristle combing machine embodying a clamping device constructed in accordance with this invention;

Figure 2 is a schematic, top elevational view of the conveyor and clamping elements of the machine of Figure 1;

Figure 3 is a vertical sectional view taken along the plane of III—III of Figure 2; and

Figure 4 is a side elevational view of the comb element.

As shown on the drawings:

In bristle combing machines of known construction, a flexible bristle conveyor 10 is employed which may conveniently comprise a pair of spaced, flexible, moving conveyor chains 10a and 10b which are separated a sufficient distance with respect to the average length of the bristles 1 to be treated so that such bristles when placed transversely past each of the conveyor chains. As viewed in Figure 2, the uncombed bristles are placed upon the conveyor chains at the left end thereof and transmitted by the conveyor chains toward the right. A frame structure 12 is provided in overlying relationship to the path of the conveyor 10 and a movable comb element 14 is mounted on such conveyor structure in conventional fashion. Thus the comb 14 is pivotally secured to an offset end of a crank plate 16 which is rotated by suitable mechanisms (not shown). The position of the teeth 14a of the comb 14 with respect to the bristles is controlled throughout the rotation of crank plate 16 by a pivoted linkage 18.

As will be understood by those skilled in the art, at least two of such moving combs 14 are provided, being spaced respectively along the length of the path of the conveyor 10. The first

comb 14 will operate from the center of the bristles transversely out to the ends of the bristles past the conveyor chain 10a while the second comb, which has not been shown in order to avoid complicating the drawings, will work from the center of the bristles outwardly to the other ends thereof past the conveyor chain 10b.

To provide a reliable clamping of the ends of the bristles while they are being worked on by the comb, this invention provides a drum 20 which is suitably journalled on a shaft 21 in the frame structure 12 for rotation about a horizontal axis and is disposed adjacent the path of movement of the comb 14. The drum 20 is laterally disposed with respect to the conveyor 10 so as to be partially lapped by one of the conveyor chains, for example the chain 10b. The other chain 10a is supported below the level of chain 10b on a pulley 15. It will be understood that an additional drum is provided at the location of the second comb and that such second drum is of identical construction to the drum 20 illustrated, but is lapped by the chain 10a.

The drum 20 is provided in its peripheral surface with an annular recess 20a to receive the conveyor chain 10b therein. The depth of this recess is preferably selected so that over a portion of the drum periphery, the chain 10b will be effectively disposed below the surface of the drum and hence the fibers 1 carried by the conveyor chain 10b will rest upon the drum surface adjacent the annular groove 20a. In accordance with this invention, such adjacent drum surface is preferably formed of a rubber or similar flexible resilient cohesive plastic composition by the application thereto of a layer of such material indicated at 22 (Figure 3). While not limited thereto, satisfactory results have been obtained by forming the band 22 of rubber of approximately 60 durometer.

To effect a clamping action upon the fibers or bristles as they pass over the flexible resilient surface of the drum 20, this invention provides an idler belt 24 which is trained over suitable pulleys 26 and 28 so as to be drawn tightly toward that portion of the drum surface which is lapped by conveyor chain 10b. Thus, in effect, a clamping region is formed between the idler belt 24 and the rubber composition surface 22 of the drum 20 wherein the ends of the fibers or bristles are tightly clamped. Such clamping area is indicated by the numeral 25 in Figure 3 of the drawings wherein the clamped bristles have not been shown for purposes of clarity. It should be noted that the bristles or fibers are clamped on that portion of the drum surface which, if extended axially would intersect a portion of the path of moving comb 14.

While any desired form of guide pulley arrangement might be utilized to effect the positioning of idler belt 24 in clamping relationship with respect to drum 20, this invention preferably mounts the pulley 26 for rotation on a fixed axis shaft 26a while the pulley 28 is rotated about an adjustable axis shaft 28a. Thus the shaft 28a upon which pulley 28 is journalled may be mounted in the end of arm 30a of an angle bracket 30, which in turn is pivotally journalled on a horizontal pin 32. A weight 34 may then be mounted upon the other arm 30b of angle bracket 32 to effect a gravitational bias of the axis of pulley 28 in the direction to effect the tightening of idler belt 24 against the drum surface 22.

In accordance with this invention, the idler

belt 24 is also formed of rubber or similar flexible resilient cohesive plastic composition. Again, the formation of belt 24 from rubber material of approximately 60 durometer has proved to provide satisfactory performance.

With the described construction it has been found that the bristles or similar fibrous material are so securely clamped between the rubber surface of drum 20 and the flexible resilient clamping belt 24 that little, if any, loss of full length fibers is produced during the combing operation. Furthermore, the combing machine embodying this invention has been able to satisfactorily comb the fibrous materials that were heretofore impossible of being combed by simple machinery.

It will, of course, be understood that various details of construction may be modified through a wide range without departing from the principles of this invention and it is, therefore, not the purpose to limit the patent granted hereon otherwise than necessitated by the scope of the appended claims.

I claim as my invention:

25 1. In a machine for combing a mass of fibers, a moving comb, a rotatable drum disposed adjacent the path of said comb, a flexible fiber conveyor lapping a portion of the drum surface, said conveyor being constructed and arranged to support fibers thereon in generally transverse relation to the path of movement of said conveyor and projecting laterally beyond said conveyor into the path of movement of said comb, a clamping belt of flexible resilient composition, and means for supporting said belt in snug overlying relationship with that portion of said conveyor lapping said drum, whereby the fibers are clamped between said clamping belt and said drum while acted on by said comb.

40 2. In a machine for combing a mass of fibers, a comb movable through a predetermined path, a rotatable drum disposed adjacent the path of said comb said drum having a peripheral groove therein, a flexible fiber conveyor engageable in said groove and lapping a portion of the drum surface, said conveyor being constructed and arranged to support fibers thereon in generally transverse relation to the path of movement of said conveyor and projecting laterally beyond said conveyor into said path of movement of said comb, a clamping belt of flexible resilient composition, and means for supporting said belt in snug overlying relationship with that portion of said conveyor lapping said drum, whereby the fibers are clamped between said clamping belt and said conveyor while acted on by said comb.

45 3. The combination defined in claim 2 wherein the surface of said drum comprises a resilient plastic composition.

50 4. In a bristle treating machine, a conveyor chain adapted to support a plurality of bristles thereon in generally transverse relation, a rotatable drum having an annular groove therein to receive said conveyor chain in partial lapping relation, whereby said chain is depressed below the surface of said drum and the bristles supported by the drum surface while moving across the partially lapped portion of the drum, a belt of flexible resilient composition, and means for positioning said belt in tight engagement with that portion of the drum surface adjacent the lapping portion of the conveyor chain, whereby the bristles are tightly clamped between said drum and belt and moved across the chain lapped portion of the drum.

5. In a bristle treating machine, a flexible conveyor chain adapted to support a plurality of bristles thereon in generally transverse relation with said bristles projecting laterally beyond said chain, a rotatable drum having an annular groove therein to receive said conveyor chain in partial lapping relation, whereby said chain is depressed below the surface of said drum and the bristles supported by the drum surface as they move across the chain lapped portion of the 10 drum, the drum surface being formed of resilient material, an idler belt of resilient composition, and pulley means for positioning said belt in tight engagement with that portion of the drum surface adjacent the lapping portion of the conveyor 15 chain, whereby the bristles are tightly clamped between said resilient drum surface and said resilient belt and moved across the chain lapped portion thereof.

6. In a machine for combing fibers, a rotatably mounted drum having a cushioned surface provided with an annular groove, a conveyor chain having a run thereof arranged and guided for reception in said groove to lap a portion of said

drum, a flexible resilient belt having a run thereof paralleling and closely spaced from said chain run and extending in snug overlying relation with said drum portion to clamp fibers between said belt and said drum portion and between said belt and said chain with said fibers extending laterally therefrom, a comb mounted for oscillating movement and means for oscillating said comb into the path of said fibers for movement outwardly toward the free ends thereof to straighten and align said fibers and comb out short insecurely held fibers.
